COMBINATION TOOTH BRUSH HANDLE AND DENTAL FLOSS DISPENSER

Irvin V. Gerlich, West Des Moines, Iowa, assignor to
Den-Tal-Ez Mfg. Co., Des Moines, Iowa

Filed Nov. 16, 1972, Ser. No. 307,139

Term of patent 14 years

Int. Cl. D24—04

U.S. Cl. D24—1 D

Fig. 1

Fig. 2

Fig. 3

Fig. 4

Fig. 5

Fig. 6

FIG. 1 is a side elevational view of a combination tooth brush handle and dental floss dispenser showing my new design;

FIG. 2 is an elevational view of the side opposite that shown in FIG. 1;

FIG. 3 is a top plan view;

FIG. 4 is a bottom plan view;

FIG. 5 is an enlarged rear end view; and

FIG. 6 is an enlarged front end view.

I claim:

The ornamental design for a combination tooth brush handle and dental floss dispenser, as shown.
